UNITED STATES PATENT OFFICE.

CORNELIUS W. VAN RANST, OF DETROIT, MICHIGAN.

METHOD OF BALANCING PISTONS.

Application filed July 7, 1925. Serial No. 41,997.

This invention relates to engines and has among its objects to provide a novel means and method for balancing the pistons of the engine.

5 In the present manufacture of a multi-cylinder internal combustion engine, it is customary to balance the weights of the pistons operating in the cylinders by removing sufficient metal from the pistons in order to 10 equalize the weights of all the pistons.

My invention provides an improved method and means for balancing the pistons of a multi-cylinder engine which consists in providing a series of weights successively 15 varying in any desired increment, the weights being adapted to be readily and selectively attached to the pistons in order to equalize the piston weights.

With these and other objects in view, the 20 invention resides in the novel features of construction and combination and arrangements of parts as more fully hereinafter described and claimed.

Referring to the drawings in which like 25 reference characters indicate corresponding parts;

Figure 1 is a side view of a piston partly 30 broken away to show one of my spring rings;

Figure 2 is a bottom plan view of the piston with a portion of the skirt broken away to show the spring ring; and

Figure 3 is a view showing in cross section a series of spring rings.

35 In the drawings reference character 10 represents a piston which may in general, be of the usual or other preferred construction employed for use in an engine preferably of the multi-cylinder type. The piston may be 40 provided with suitable means such as an annular groove 11 within the skirt 12 and preferably adjacent the lower portion thereof, this groove being adapted to selectively receive any number of weight members 45 which, for convenience, may be in the nature of split rings 13, 14 and 15 as shown in Figure 3. These rings may be formed of a resilient material such as wire and preferably vary in weight by a predetermined increment such, for example, as one-eighth of an ounce.

The pistons after being completely machined and fitted to the cylinders, are weighed and are then increased in weight to 50 a predetermined standard by adding a ring of sufficient weight. If it is desired to add

a weight in between that of the two nearest rings, the heavier may be used and a portion of the wire cut off, or a second series of rings may be employed varying in increments of 60 weight in between the weights of the first series. The resiliency of the rings permits ready application to the piston annular groove where they will be securely held in place due to the resilience of the rings. 65

Various methods of balancing the pistons within the scope of my invention will be readily apparent. For example, all of the pistons may be brought up to the weight of the heaviest piston of a multi-cylinder engine, or all of the pistons may be machined slightly underweight and all brought up to the predetermined standard weight. 70

While it is believed that from the foregoing description, the nature and advantage 75 of my invention will be readily understood, I desire to have it understood that I do not limit myself to what is herein shown and described and that such changes may be resorted to when desired as fall within the 80 scope of the claims.

What I claim as my invention is:

1. The process of producing a piston having a predetermined standard weight which consists in forming the piston below the desired weight, forming an engageable member on the piston adapted to support a weight member and then engaging with the said engageable member a weight member of sufficient mass to bring the piston up to the 90 desired standard weight.

2. The process of producing a piston of a predetermined standard weight which consists in forming the piston below the desired weight, forming a socket in the piston, and then mounting in the socket a weight of sufficient mass to bring the piston up to the desired standard weight. 95

3. The process of producing a plurality of pistons of equal standard weight which 100 consists in forming each of the said pistons below the desired standard weight, forming an engageable part on each piston for engagement in by a weight, forming a series of weights independently engageable with the said engageable part and varying in accordance with a predetermined increment and then engaging in the engageable part of each piston that weight of the series which is sufficient to bring the piston up to the 110 desired standard weight.

4. The process of producing a plurality

of pistons of equal standard weight which consists in forming each of the said pistons below the desired standard weight, forming a groove in each piston, forming a series 5 of spring rings varying in weight in accordance with a predetermined increment, and then mounting in the groove of each piston that ring of the series which has mass sufficient to bring the piston up to the 10 desired standard weight.

5. The method of balancing a plurality of pistons for use in a multi-cylinder engine consisting in machining and weighing the pistons and then adding one of a series of 15 spring rings varying in weight to one or more of the pistons in order to equalize the weights of all of the pistons.

6. The combination with a piston having a portion modified for engagement with a 20 weight member, of a weight member automatically engageable with said portion.

7. The combination with a piston, of 25 means on the piston adapted for engagement with a weight member, and a series of weight members whose weights vary in accordance with a predetermined increment, each of the said weight members being adapted for unassisted engagement with the 30 said engaging means.

8. The combination with a piston whose 35 weight is below a desired predetermined value, of a member formed on the piston adapted for engagement with a weight, and a weight adapted for independent engagement with the said member, the said weight having a value sufficient to bring the piston up to the desired predetermined value.

9. In combination with a piston formed with an annular groove, a series of spring 40 rings adapted for engagement in said groove, said rings varying in their weights according to a predetermined increment.

10. In combination with a piston formed with an annular groove, a series of weight members adapted for engagement in said 45 groove, said weight members varying in their weights according to a predetermined increment.

11. In combination with a piston formed with an annular groove, a series of rings 50 adapted for engagement in said groove, said rings varying in their weights according to a predetermined increment.

12. In combination, a piston and a series 55 of annular weight members, said piston being provided with means accommodating selective attachment of said members.

13. The combination with a piston having means accommodating selective attachment of one of a series of weight members whose 60 weights vary in accordance with a predetermined increment, of a series of resilient weight members of varying weight adapted for attachment to the piston.

14. The combination with a piston, of a 65 series of expandible weight members adapted for selective attachment to the piston for bringing the weight of the piston up to a predetermined value, said weight members adapted to be expanded into clamping engagement with the piston. 70

In testimony whereof I affix my signature.

CORNELIUS W. VAN RANST.
